UNITED STATES PATENT OFFICE.

MATT MATTHIAS MARTY, OF McGREGOR, IOWA.

WIRE-STRETCHER.

940,884.

Specification of Letters Patent. Patented Nov. 23, 1909.

Application filed June 12, 1909. Serial No. 501,791.

To all whom it may concern:

Be it known that I, MATT MATTHIAS MARTY, a citizen of the United States, residing at McGregor, in the county of Clayton, State of Iowa, have invented certain new and useful Improvements in Wire-Stretchers; and I do hereby declare the following to be a full, clear, and exact description of the invention, such as will enable others skilled in the art to which it appertains to make and use the same.

This invention relates to wire stretchers, employed for stretching the strand wires of wire fences and for similar purposes, and has for one of its objects to simplify and improve the construction and increase the efficiency and utility of devices of this character.

Another object of the invention is to provide a device of this character which is capable of stretching the strand wires beyond terminal or corner posts, so that the wire may be stapled to the last post, or to a corner post in a line of fencing.

With these and other objects in view, the invention consists in certain novel features of construction as hereafter shown and described and then specifically pointed out in the claims, and in the drawings illustrative of the preferred embodiment of the invention, Figure 1 is a side elevation of the improved device, applied. Fig. 2 is a plan view of the same. Fig. 3 is a section on the line 3—3 of Fig. 1.

The improved device comprises a frame formed with spaced side members 10—11 and curved laterally at one end as shown at 12—13. Extending through the side members intermediate their ends is a main shaft 14 carrying a winding drum 15 and a relatively large gear wheel 16 between the side members. Extending through the side members adjacent to the shaft 14 is a drive shaft 17 having its ends 18—19 adapted to receive a turning crank or other suitable implement 20, the crank being detachable from the shaft and applicable to either end of the same. The shaft 17 carries a gear pinion 21 engaging with the gear 16, so that the rotation of the shaft 17 produces the requisite motion to the drum 15 at a relatively slow speed. The drum 15 is provided with a curved rod 22 terminating at its free end in a notch in one rim of the drum, the curved rod being adapted to receive one of the links

of a chain 23, the chain being thus coupled detachably to the drum.

Connected to the side member 10 is a bar 24 curving laterally at one end and terminating in a presser foot 25, while a similar bar 26 bears against the outer face of the side member 11 and is curved laterally and terminating in a presser foot 27, the presser feet 25—27 extending in opposite directions away from the members 10—11, and designed to bear against the supporting post or other stationary structure 28, the object to be hereafter explained.

Adjustably disposed upon the curved portions 12—13 of the side members 10—11 are sleeves 29—30, the sleeves being provided with set screws 31—32 by which they may be adjustably coupled to the portions 12—13. Extending from each of the sleeves 29—30 is a spur one of which is represented at 33, and adapted to engage against the opposite side of the post 28 from the presser feet 25—27.

Extending through the side members 11—12 at the end opposite to the curved portions 12—13 is a rod 34, and swinging upon this rod are two arms 35—36, the free ends of the arms being arranged to converge toward each other and pivotally connected at 37 to a swivel head 38. Mounted for rotation in the swivel head 38 is a straining rod 39 having the outer portion threaded as shown at 40 and with a square terminal 41 to receive a turning crank, the square portion being preferably of a size to receive the same turning crank 20. Located in parallel relations to the rod 39 is a bar 42 having a hook terminal 43 adapted to engage against the post 28 and with laterally extending lugs 44—45 and through which the rod 39 extends. One of the lugs is threaded to engage the rod, so that by rotating the rod by means of the crank 20 applied to the square end 41 the hook terminal 43 may be adjusted to correspond to the structure 28. By this simple means, a very great stress may be applied to lock the members 10—11 and their attachments to the stationary member 28. The stationary member may be a corner post, and the main portions of the device located beyond the post, so that when the required strain is secured the wire is located across the post 28, and can be secured by the usual staples or other fastening means before the strain is released.

The side members 10—11 are each pro-

110

vided with a plurality of apertures 47 to receive the clamp bolts 48 by which the member 24-26 are secured, so that these members may be adjusted longitudinally and adjustably secured to the side members. Swinging from the side member 11 is a pawl 49 adapted to engage the gear 16, and thus hold the drum from retrograde movement.

The chain 23 is provided at its free end 10 with a suitable wire clamp device by which the chain is designed to be coupled to the wire which is to be strained.

Attached to one of the members 10 or 11, for illustration the member 10, is a wire clamp device 46 to which the wire which has been strained may be coupled when it is required to take a fresh grip on the wire.

The improved device is simple in construction, will be constructed entirely of metal, and is strong, and durable, and can be constructed of any required size, and will be found of great advantage in connection with wire fence structures.

What is claimed is:—

25 1. A wire stretcher comprising a frame formed with spaced side members curved laterally at one end, spurs adjustably connected to said curved portions and adapted to engage a stationary structure from one side, a straining member mounted to swing from said frame members, a hooked member adapted to engage a stationary structure, means for adjustably coupling said hooked member to said straining member, stop 30 members carried by said frame and adapted to engage a stationary structure at the side opposite to the hooks and spurs, and wire straining devices carried by said frame.

2. A wire stretcher comprising a frame 40 formed with spaced side members curved laterally at one end, sleeves adjustably connected to said curved portions and provided with spurs adapted to engage a stationary structure from one side, a straining member 45 mounted to swing from said frame members,

a hooked member adapted to engage a stationary structure, means for adjustably coupling said hooked member to said straining member, stop members carried by said frame and adapted to engage against a stationary structure at the side opposite to the hooks and spurs, and wire straining devices carried by said frame.

3. A wire stretcher comprising a frame formed with spaced side members curved laterally at one end, spurs adjustably connected to said curved portions and adapted to engage a stationary structure from one side, a straining member mounted to swing from said frame members and rotative relative thereto and threaded for a portion of its length, a bar having a threaded projection through which said threaded portion passes and provided with a terminal hook adapted to engage against a stationary structure, and wire straining devices carried by said frame.

4. A wire stretcher comprising a frame formed with spaced side members curved laterally at one end, spurs adjustably connected to said curved portions and adapted to engage a stationary structure from one side, two bars mounted to swing from said frame members and converging at their free ends, a swivel device swinging between said converging ends, a straining member rotatively engaging said swivel device and threaded for a portion of its length, a bar having a threaded projection through which said threaded portion passes and provided with a terminal hook adapted to engage against a stationary structure, and wire straining devices carried by said frame.

In testimony whereof, I affix my signature, in presence of two witnesses.

MATT MATTHIAS MARTY.
